US00D615837S

(12) **United States Design Patent**
Lopano et al.

(10) **Patent No.:** **US D615,837 S**
(45) **Date of Patent:** **** May 18, 2010**

(54) **POWER TOOL HANDLE**

(75) Inventors: **Daniel N. Lopano**, Bel Air, MD (US);
Gabriel E. Concari, Eldersburg, MD
(US); **Sion Netzler**, Abingdon, MD (US)

(73) Assignee: **Black & Decker Inc.**, Newark, DE (US)

(**) Term: **14 Years**

(21) Appl. No.: **29/351,984**

(22) Filed: **Dec. 15, 2009**

Related U.S. Application Data

(63) Continuation of application No. 29/332,734, filed on Feb. 24, 2009, now Pat. No. Des. 609,544.

(51) **LOC (9) Cl.** **08-04**

(52) **U.S. Cl.** **D8/68**

(57) **CLAIM**

The ornamental design for a power tool handle, as shown and described.

DESCRIPTION

FIG. 1 is a perspective view of the a power tool handle.

FIG. 2 is a front view of the handle.

FIG. 3 is a rear view of the handle.

FIG. 4 is a left view of the handle.

FIG. 5 is a right view of the handle.

FIG. 6 is a top view of the handle; and,

FIG. 7 is a bottom view of the handle.

The portions in broken lines do not form any part of the claimed design.

1 Claim, 5 Drawing Sheets
